APPARATUS FOR THE DRYING OF PAPER
OR FABRICS

Frank W. Partsch, Jackson Heights, N. Y., assignor to J. O. Ross Engineering Corporation, New York, N. Y., a corporation of New York

Application April 19, 1935, Serial No. 17,161

5 Claims. (Cl. 34—48)

This invention relates to a method and apparatus for the drying of paper or fabrics with the requirements usually encountered in the drying of sized and impregnated papers.

5 In the drying of sized and impregnated papers, certain difficulties occur. It is advantageous to control and vary the temperature and humidity in different parts of the cycle of drying while at the same time motivating the paper through the 10 dryer without injury to the traveling web of paper. For efficiency and high quality of product the application of the drying medium with respect to the surface of the web is also of great importance. There should not be a drying in spots but there 15 should be a uniform drying of the web, both transversely and longitudinally. Ordinarily, temperatures as high as possible should be maintained in order to reduce the time element, length of dryer, and increase the speed of drying, but these 20 temperatures must be controlled within certain limits as there are certain critical temperatures that should not be exceeded for quality products, and these critical temperatures may and often are different in different parts of the cycle of drying. 25 The dryer should be sufficiently flexible so that variation in temperature and humidity can be controlled independently in different sections of the dryer whereby the drying of the material 30 takes place under most conditions from the interior outward of the paper. Under certain conditions, dependent on the type of surface that may be desired in the product however it may be necessary to first dry the surface relatively quickly and then more slowly remove the moisture from 35 within. In a dryer adapted to sized and impregnated papers, it is advantageous if the dryer may be so regulated with temperature and humidity so as to produce either of the two methods of drying 40 to produce in the same dryer at different times the different types of surfaces of product desired. The rate of drying as well as the relative rate of drying the interior as compared to drying the surface is to a large extent dependent upon the temperature of the drying medium, the humidity of 45 the drying medium, the velocity of travel of the drying medium on the surface of the material being dried, the degree of impingement of the drying medium, the movement of the material being 50 dried, and the movement of the moist film that forms on the surface of the goods.

One of the objects of this invention is to provide a dryer especially adapted for the drying of sized and impregnated paper but which would also 55 be used when drying other materials where the

same requirements are met as in the drying of sized and impregnated paper.

A second object of this invention is to provide a dryer consisting of units whereby the apparatus and principles of this invention may be applied independently in the various sections to get the proper conditions in the various parts of the cycle of drying, and also that they may be varied in connection with the various types, thicknesses, kinds and forms of paper impregnations or coatings.

Still another object of the invention is to provide a dryer or dryer system which can be controlled either manually or by automatic control with respect to either the temperature or humidity, or both, either in a fixed relationship to each other or an entirely independent control as required by the material to be dried.

A still further object of the invention is to provide means whereby the air supplied is provided alternately from the front and back of the dryer so as to make still more uniform the distribution of the air to the web to eliminate the possibilities of uneven drying transversely.

A still further object of the invention is to provide air nozzles which may be rotated to direct the impingement of the air supply at a different angle to the web of material, or to direct it to another portion of the web in order to avoid the formation of wrinkles and like objectionable features.

A still further object of the invention is to control the volume and velocity of the air so that more or less may be discharged to either side of the web, or to either edge of the web.

A still further object of the invention is to provide a dryer or dryer system consisting of sections whereby the recirculated air may be taken from one section and after mixing with the required fresh air and properly treating the air supply of then supplying this air to an adjoining section or, to meet certain requirements of the product desired, to take the air from one section, mix with the required fresh air properly treated and supply it to the same section.

Referring to the drawings:

Figure 1 is a view partly in elevation and partly in section of a dryer embodying the principles of my invention.

Figure 2 is a plan view of Figure 1.

Figure 3 is a cross sectional view of Figure 1 along the line 3, 3, looking in the direction of the arrows.

Figure 4 is a sectional view of a modified form of the device.

Figure 5 is a plan view of a modified form of nozzle arrangement.

Figure 6 is a modified form similar to Figure 1.

Figure 7 is a view in elevation of a rotatable 5 nozzle.

In carrying out my invention, I propose to utilize a dryer formed of sections A, B, C, D, etc., which sections are surrounded by a housing or chamber 1. Within the housing or chamber 10 1, I provide carrier rolls 2 about which are carried the sized or impregnated web of paper 3 whereby the web is formed into loops and motivated through the dryer. At the top of each section A, B, C, D, etc., I provide headers 4, 4', 15 from which nozzles 5, 5', protrude alternately, that is, a nozzle 5 protrudes from header 4, then a nozzle 5' protrudes from header 4', etc. The using of alternate nozzles connected to opposite headers for their air supply gives a more even 20 distribution. In addition, the individual nozzles are tapered to secure a uniform emission of heating medium from each orifice. The carrier rolls 2 are driven in any well known manner. At the top of each section A, B, C, D, etc., are similar 25 headers 6, 6', also carrying nozzles 1, 1'. These nozzles are similar to nozzles 5, 5', in arrangement. The nozzles 5, 5', from the top headers 4, 4', cause the heating medium to impinge or wipe one side of the web while the bottom nozzles 30 7, 7', cause the heating medium to impinge or wipe the other side of the web 3. The nozzles are rotatable being journaled in the headers. A slot 31 and set screw 32 can be utilized for locking them in the desired position or any other 35 well known locking device may be used. It is desirable to change the angle of impingement to prevent the formation of wrinkles and to procure the most satisfactory and efficient drying effect. The angle with which the air should strike the 40 moving web depends on the class of goods and the wiping effect desired and distribution of the heating medium. Dampers 8, 8', 9, 9', control the distribution so that it is possible to vary the distribution from the header to the nozzles individually 45 whereby some of the loops of web 3 may not receive any air and other loops may receive much air. The nozzles 5 and 7 have orifices 10. These individual orifices are of such shape and design that they are adapted to be stopped or 50 have deflectors 30 whereby the distribution of air throughout the length of the nozzle, or in other words, over the width of the sheet, may be controlled. The deflection or stopping of the orifices 10 permits the dryer to be used for different widths of goods, and permits controlling 55 of the drying effect on the edges, and varying the volume and velocity of the drying medium emitted from the open orifices.

The apparatus is designed to control the volume and velocity of the air heating medium in its discharge upon either side of the sheet, this being controlled by controlling the volume and velocity to the alternate nozzles, and the volume and velocity from the alternate nozzles by said 65 deflectors or stops.

The drying medium is supplied to headers 4 by conduits 11 and headers 4' are supplied with drying medium through conduits 11'. Conduits 11, 11', lead from the discharge of a fan or blower 12. Dampers 13, 13', control the quantity 70 of heating medium delivered to headers 4, 4', and are located in conduits 11, 11', respectively. Conduits 11, 11', also supply headers 6, 6'. Dampers 14, 14', likewise control the volume to 75 headers 6, 6'. Damper 15 is a distribution

damper controlling the proportions of heating medium distributed by conduits 11, 11', thereby controlling the heating medium directed to either the front or back of the machine.

The circulation of the heating medium is as follows:

The gases are withdrawn through openings 16 in the bottom, or may be located at one side of or above the dryer, into mixing chamber 17 and thence through filter 33 and heater 18 into fan 12. 10 Opening 19 permits the admission of fresh or room air to mixing chamber 17 where it mixes with recirculated air thence through filter 33 and heater 18 to fan or blower 12. From fan 12 the mixture is recirculated through conduits 11, 11', 15 distributing the heating medium to headers 4, 4', 6, 6', which in turn feed nozzles 5, 5', 7, 7', completing the cycle. The nozzles 5, 5', 7, 7', are tapered to secure a uniform emission of heating medium from each orifice 10. There is a nozzle 20 for each loop of the travelling web whereby the heating medium impinges on both sides of the web. The openings to the mixing chamber 17, to wit, 19 and 20, have dampers 19', 20', and automatic damper controls and are conjointly 25 operated to proportion the air admitted through the openings. If desired, the dampers may be manually operated. The fresh or room air may be filtered before admission to mixing chamber 17 as shown. The dampers 19', 20', when automatically operated are done so through the customary humidistats 21 and pneumatic control systems whereby the humidity may function to control the dampers. This is shown by humidistat 21 operating damper motor 22 which operates dampers 19', 20', through well known linkage. The temperature of the heating medium is controlled by thermostat 23 through pneumatic means 24 to operate steam valve 25. It is understood that although steam has been shown as 30 a means for heating the heating medium, any well known form of heating device may be used. The dual control of the temperature and humidity preferably operates independently although it may be arranged to operate conjointly, if desired. 35 It is also desirable that valve 25 be of such design that it may be also operated manually as well. This may be required for repairs or to shut off a particular heater of one section permitting the other sections to operate. In order to prevent 40 too high a moisture content of the recirculated gases and to prevent the building up of too great a plenum pressure, I propose to provide a vent or stack 26 to relieve the atmosphere in housing or chamber 1. I also provide a damper 27 which 45 is preferably automatically controlled by a thermostat 27' but may be manually operated.

In the modified form shown in Figure 4 instead of alternate nozzles from headers 4, 4', 6, 6', the headers may be joined by pipes forming 60 nozzles 28 with the same orifices as the heretofore described nozzles. These pipes or nozzles 28 may also be rotatable (as shown in Figure 7) to direct the streams of heating medium issuing from the orifices 10 in the desired direction. 65 The orifices in pipes or nozzles 28, may also be stopped or deflected similarly as were nozzles 5, 5', 7, 7'. In other respects, this modification is identical with Figures 1 and 3 inclusive.

It is understood that the sections A, B, C, D, 70 etc., may be increased or reduced in number or size as desired and in place of the individual mixing chambers, heaters, fans or blowers, a single mixing chamber heater and fan may be utilized to supply a plurality of sections. In addition, 75

where variable temperature and humidity control throughout the length of the dryer may not be required, the number of automatic control instruments may be reduced to one set or more as necessary. In other words, the method and apparatus is subject to variation permitting its use over a wide field in connection with drying in the paper industry and adapting itself not only to new installation but to the conversion of some types of dryers that are at present in use. An illustration of the variation is Figure 5 where in the nozzles 34 from the top header 4' run in opposite direction from the bottom nozzles 35 connected to bottom header 6. In the next section the nozzles are reversed in direction, that is the top nozzles 34' are connected to header 4 and the bottom nozzles 35' are connected to header 6'. The remaining sections also alternate in the change of direction of the nozzles. That is, each alternate section has the nozzles extending in opposite directions thereby the distribution of the heating medium is more even than would be the case were they all extending in the same directions.

25 In the modified form shown in Figure 6 by means of conduit 36 connecting the recirculation ducts 16, the recirculated air may be taken from one section and recirculated through an adjacent section. In other words, the recirculated air is
30 taken from one section and after mixing with the required fresh air and properly treated the air supply is then supplied as heating medium to an adjoining section. The heating medium is thus primarily taken in at one end, circulated
35 through that section, withdrawn from that section, properly treated to the desired temperature and humidity, supplied to the next section as a drying medium, removed from that section, again properly treated to produce the desired
40 temperature and humidity and then supplied to the adjoining section as a drying medium supply and this is continued until the section at the end farthest from the fresh air supply at which point the drying medium may be vented and dis-
45 charged to atmosphere. This method of heating medium circulation is in a cycle progressing with the direction of travel of the goods and permits of the maintenance of heating medium supply in an effective condition for the maximum and de-
50 sired results. Obviously, the direction of travel of the material being dried may be changed, if desired, to a countercurrent method by reversing the direction of the material through the dryer.

With my invention, not only is there a control of the temperature throughout the dryer but there is also a continuous rehabilitation of the drying medium so that it is controlled effectively with respect to humidity, temperature, admission of fresh air, removal of dust, and a closer maintenance of the required conditions throughout the length of the dryer.

In Figure 6, I have shown the admission of the fresh air through a filter 37 into a fresh air conduit 38 with leads to the respective stations A,

B, C, D, etc., and into the mixing chambers 17. With this arrangement, the air may be filtered prior to the admission to the mixing chambers.

As the wastage when a break occurs in the drying of paper causes considerable loss, the proper drying of the web becomes important from this angle alone. The web when wet, or dried in spots, is easily torn or injured and unless properly dried is unsatisfactory in quality. The combined moisture in the paper should not be entirely removed for if the paper is dried to such an extent that all the moisture is removed it becomes generally brittle. It, therefore, is preferable to not only control the temperature, but also the humidity in the dryer and by the use of the recirculated gases, moisture in the sheet may be maintained and controlled. A great deal of the heating value of the heating medium is conserved in the recirculation of gases, thereby increasing the efficiency of the dryer. Also by my invention, the time of drying or speed of travel of the web can be increased permitting a higher output from the dryer.

Various modifications may be made and still fall within the scope of my invention. 25

What I claim is:

1. A drier for a web material comprising a chamber, a set of parallel rollers adjacent the top of said chamber, a second set of parallel rollers adjacent the bottom of said chamber, said rollers being arranged to support a web in a series of loops, a set of nozzles substantially parallel to and arranged above said first set of rollers, a second set of nozzles substantially parallel to and arranged below said second set of rollers, each nozzle being provided with a longitudinal row of discharge ports for supplying air to said web and each nozzle being rotatable about its longitudinal axis to vary the angle of impingement of the air upon said web and means for supplying heated air to said nozzles. 40

2. A drier according to claim 1 in which said nozzles are tapered and means are provided for controlling emission throughout the length of each nozzle.

3. A drier according to claim 1 in which said air supplying means comprises a mixing chamber, a heater, a fan, a recirculating conduit from the drying chamber to said mixing chamber, a fresh air inlet to said mixing chamber, and conduits leading from said fan to said nozzles. 50

4. A drier according to claim 1 in which said air supplying means comprises a mixing chamber, a heater, a fan, a recirculating conduit from the drying chamber to said mixing chamber, a fresh air inlet to said mixing chamber, conduits leading from said fan to said nozzles, and means for apportioning the volume of air supplied to said conduits.

5. A drier according to claim 1 characterized by means for regulating the temperature and humidity within said drying chamber. 60

FRANK W. PARTSCH.
